FLUID CONTROLLED WINCH

Bryant L. Britt, Maplewood, Mo., assignor to
 Wagner Electric Corporation, St. Louis, Mo., a
 corporation of Delaware

Application March 1, 1945, Serial No. 580,369.

5 Claims. (Cl. 254—187)

1

This invention relates to hoisting or winch mechanisms and in its more specific aspects is directed to the construction of a winding drum for a winch to materially increase the cable receiving capacity thereof.

One of the objects of this invention is to produce a winch capable of holding a larger amount of cable with the same amount of material as is now employed in prior art devices.

Another object of the invention is to provide a winch in which the clutch and brake mechanisms comprise standard automotive brake equipment for the braking and operation of the winding drum.

Another object of the invention is to produce a winch in which the clutch and brake mechanisms are disposed within the winding drum.

A further object of the invention is to provide a winch in which the clutch and brake mechanism each comprise standardized hydraulic brake constructions.

A still further object of the invention is to provide a winch having a winding drum thereon which extends substantially the entire length of the mechanism and has the clutch and brake devices oppositely disposed within the length of the winch per se.

Still another object of the invention is to provide a winch having hydraulically operated brake units functioning as brake and clutch elements, each unit disposed within the length of the winch and individually selectively operable to cause the winding drum to be rotated or stopped depending upon which set of brake elements is operative.

Another and still further object of the invention is to provide a winch construction in which the winding reel or drum has its motion controlled by two sets of hydraulically actuated brake elements, one set of which functions as a clutch and the other set of which functions as a brake both operative on the interior surface of the winding drum.

Other and further objects of the invention will occur to those skilled in the art to which this application pertains as the description proceeds, which, taken in connection with the accompanying drawings, sets forth a preferred embodiment of the invention but such disclosure is not to be construed as a limitation of the invention which is limited only by the appended claims, and any and all modifications, alterations and variations of structure coming within the spirit and scope thereof are deemed to be included herein.

In the drawings:

Figure 1 is an end elevational view of the winch;

Figure 2 is a plan view thereof, partly in section, to show the details of construction;

Figure 3 is a sectional view taken substantially along the line 3—3 of Figure 2; and

Figure 4 is a sectional view taken substantially along the line 4—4 of Figure 2.

Prior practices in the construction of winch mechanisms employed on portable and stationary hoists have restricted the capacities of their winding reels by reason of the fact that the clutch and brake constructions have been mounted on or near the ends thereof, thereby consuming space that could not be used for the winding of the cable. This necessarily required the construction of large bulky devices when it was found desirable to have a winch on which a considerable amount of cable was to be wound in order to handle material located at more than the customary distances from the hoist. In the instant disclosure there is provided a winch having a winding drum thereon in which the cable capacity has been increased by approximately one-third without increasing the quantity of material used in its construction. Both the clutch and the brake construction utilize standard hydraulically operated brake equipment for transmitting rotative movement to the winding reel or drum as well as for the arrest and prevention of rotation therein. These brake structures are disposed concentrically of the winding reel or drum and are contained within the length thereof, thereby enabling the cable to be wound over considerably more of the length of the reel and increasing the cable winding capacity as well as the compactness of the device, all as a result of moving the clutch and brake constructions to the interior of the winding reel.

The above objects and advantages are achieved in the construction set forth in the accompanying drawings in which 1 is an appropriate base in the form of a plate on which a pair of upright members 2 and 3 are secured by means of a plurality of cap screws 4 and 5. The uprights 2 and 3 are in reality bearing supports for the rotating mechanism of the winch and to accomplish this upright 2 has a sleeve 6 welded in an aperture 7 cut therein. The upright 3 has a sleeve 8 inserted in an aperture 9 cut in the upright and welded therein. The sleeve 8 is of considerably greater length than sleeve 6 to allow proper spacing of the clutch and brake elements subsequently set forth. Sleeves 6 and 8 constitute bearing members for a shaft or tube 10 which has a flange 11 thereon at its one end and at its other end has a gear 12 secured thereto. Appropriate thrust bearings 55 may be provided between the flange 11, gear 12,

and uprights 2 and 3 if desired. Ring element 13 is intended to function as a thrust member and a similar construction can be provided between flange 11 and upright 3. Gear 12 meshes with idler pinion 14 journaled on an appropriate pin 15 fixed to upright 2. Pinion 15 meshes with another pinion 16 secured to the armature shaft of motor 17. It is clear from the foregoing, therefore, that shaft 10 is rotated by motor 17 through the several gear elements described. Suitable lubricant retainers 18 and 19 are provided in the several sleeve constructions that also serve as aids in keeping shaft 10 properly centered with respect to sleeves 6 and 8.

The winding drum or reel 20, which is disposed between uprights 2 and 3, is rotated in suitable bearing elements 21 and 22. These bearing elements are preferably in the form of large rings secured to uprights 2 and 3 as particularly shown in section in Figure 3. The winding reel 20 comprises a cylinder 23, the ends of which are received in the ring bearings 21 and 22. The sleeve element 23 has collars 24 and 25 thereon so positioned that they are adjacent bearing elements 21 and 22 and further arranged such that there is a minimum of end play between the bearing elements and collars 24 and 25. If necessary, appropriate thrust bearing elements may be inserted in the slots 26 and 27 which may be of well-known construction. The cable 28, which is shown wound on reel or drum 20, is conventional in the art.

The braking of the winding reel is accomplished by a pair of brake assemblies each comprising a pair of shoes 29 and 30 customarily used in automotive type vehicles and preferably hydraulically actuated by means of a brake cylinder 31 having a pair of pistons (not shown) arranged therein whose rods engage the ends of the brake shoes. The other ends of the brake shoes are pivoted on anchor pins 32 secured to the backing plate 33, which backing plate is fixed to a collar 34 integrally associated with sleeve 8. A plurality of cap screws 35 secure the backing plates 33 to the two collars 34. The brake cylinders 31 are received in appropriate recesses in the backing plate and only a single anchor pin 32 is shown for reasons of simplicity. Other types of brake assemblies may be employed with equal facility.

Pressure fluid for actuating the pistons in the brake cylinders is derived from a master cylinder or compensator 36 arranged somewhere near or adjacent the operator's station and pressure fluid generated by the master cylinder upon action of pedal 37 is conducted through conduit 38 into a second conduit 39 fixed in upright 3 and is thence conducted to a fitting 40 and by means of conduits 41 and 42 is then conducted to the brake cylinders 31. The master cylinders may be of the type set forth in United States Patent No. 1,758,871, issued May 13, 1930, which shows a construction well known in the art. The brake surface with which shoes 29 and 30 engage is formed on the interior surface of cylinder 23 of the drum or reel 20. The operation of these brakes is the same as in the automotive art which is believed to be well known to the hoisting art.

The power output of motor or prime mover 17 is supplied to reel 20 through the gear train 12, 14, and 16 from shaft 10 through a clutch which is made up of a dual clutch shoe assembly. Shaft 10 has an enlargement 43 thereon, disposed in the space between the ends of sleeves 6 and 8 interiorly of reel 20, to which a pair of backing plates or supports 44 and 45 are secured by means

of a plurality of cap screws 46 and 47. Each set of clutches comprises a pair of clutch shoes 48 and 49 which are anchored to the backing plate by means of a pin 50 and hinged thereto in a conventional manner. A clutch motor 51 is disposed between the ends of clutch shoes 48 and 49 to force them into engagement with cylinder 23 of reel 20. The pistons (not shown) are arranged within clutch cylinder 51, the rods of which pistons engage the ends of clutch shoes 48 and 49 in a well-known manner. The clutch shoes pivot about the anchor pin 50 and upon the energization of the motor 51, may engage the interior of the cylindrical element 23.

Pressure fluid admitted to motors 51 is derived from a master cylinder or compensator 52 actuated by the pedal device 53. The pressure fluid generated thereby is conducted through conduit 54 thence through conduit 55 into a hydraulic coupling 56. The coupling is necessary for the reason that shaft 10 and gear 12 must rotate with respect to conduit 55 and the parts associated therewith. Coupling 56 may be of any construction well known in the art or as illustrated and pressure fluid therefrom is conducted through conduit 57 into a fitting 58, thence through a duct 59 formed in the enlargement or collar 43 and then into a fitting 60 and thereafter by means of conduits 61 and 62 into the clutch cylinders 51. In view of the fact that clutch shoes 48 and 49 are secured to shaft 10, they will, when brought into engagement with the interior surface of the cylinder 23 of reel 20, cause the reel to rotate. Compensators 52 and 36 are preferably disposed adjacent the operator's station so he will be able to suitably control the operation of brakes 29 and 30 which will arrest rotation of reel 20 or he can operate clutch shoes 48 and 49 with equal facility and cause them to perform as a clutch to rotate reel 20 from prime mover or motor 17.

From the foregoing description and disclosure it is clear that a winch has been provided which employs standard automotive type brake equipment so constructed and arranged as to enable one set of shoes to be employed as a brake and the other set of shoes to be employed as a clutch. The operation and construction of the foregoing device is thought to be clear from the disclosure to enable anyone skilled in the art to practice the invention.

Having fully described my invention, that which I claim as novel and desire to protect by Letters Patent of the United States is:

1. In a winch, a pair of uprights; a winding reel provided with an interior cylindrical surface; means to journal said winding reel on said upright; a shaft; means to journal said shaft in said uprights which comprises a pair of sleeve members each of which is secured to one of said uprights; means to rotate said shaft; a plurality of brake elements mounted on one of said sleeve members and engageable with the interior cylindrical surface of said winding reel to arrest rotation thereof; means to actuate said brake elements; a clutch comprising a pair of clutch elements mounted on said shaft engageable with the interior cylindrical surface of said winding reel; and means to actuate said clutch elements to enable the rotative motion of said shaft to be transmitted to said winding reel.

2. In a winch, a pair of uprights; a sleeve secured to each of said uprights; a shaft rotatably mounted in said sleeves; means to rotate said shaft; a winding reel rotatably mounted on said

uprights; a brake secured to one of said sleeves and engageable with said reel; means to actuate said brake to arrest or prevent motion in said reel; a clutch comprising a pair of clutch shoes secured to said shaft and engageable with said reel; and means to actuate said clutch shoes.

3. In a winch, a pair of uprights; a sleeve secured to each upright; a shaft journaled in said sleeves; means to rotate said shaft; a winding reel provided with an interior surface and rotatably mounted on said uprights; a brake comprising a plurality of shoes mounted on one of said sleeves engageable with the interior surface of said reel; means to actuate said brake shoes to bring said shoes into engagement with the interior surface of said reel to arrest or prevent motion of said drum; a clutch comprising a plurality of clutch shoes mounted on said shaft engageable with the interior surface of said reel; and means to actuate said clutch shoes into engagement with said reel interior surface to cause said reel to be rotated by said shaft.

4. In a winch, a pair of uprights; means to journal a winding reel on said uprights; a shaft rotatably mounted in said uprights; a sleeve secured to one of said uprights and receiving said shaft; means to rotate said shaft; a brake mechanism associated with said sleeve and engageable with said reel to arrest or prevent rotative motion of said reel; means to actuate said brake mechanism; a clutch comprising a plurality of clutch

shoes mounted on said shaft; and means to actuate said clutch shoes to bring them into engagement with said drum.

5. In a winch, a pair of uprights; means to journal a winding reel on said uprights; a shaft; means to rotate said shaft; sleeve elements in said uprights to receive said shaft; a brake mechanism mounted on one of said sleeves and engageable with said reel; hydraulic means to actuate said brake mechanism to arrest or prevent rotative motion in said reel; a clutch comprising a pair of clutch shoes secured to said shaft; hydraulic means to actuate said clutch to bring said clutch shoes into engagement with said reel in order to rotate said reel.

BRYANT L. BRITT.
